(57) **CLAIM**

The ornamental design for a multi-function imaging and printing device, substantially as shown and described.

DESCRIPTION

FIG. 1 is a left-front perspective view of the design for the multi-function imaging and printing device with a control panel in a first position;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a left-front perspective view of the design for the multi-function imaging and printing device with the control panel in a second position.

The portions shown in broken lines are for illustrative purposes only and form no part of the claimed design.
